UNITED STATES PATENT OFFICE.

LELAND A. BABCOCK, OF CHICAGO, ILLINOIS, ASSIGNOR TO SPRAGUE CANNING MACHINERY COMPANY, CHICAGO, ILLINOIS, A CORPORATION OF ILLINOIS.

PULPING MACHINE.

Application filed May 21, 1920. Serial No. 383,139.

To all whom it may concern:

Be it known that I, LELAND A. BABCOCK, a citizen of the United States, residing at Chicago, in the county of Cook and State of Illinois, have invented new and useful Improvements in Pulping Machines, of which the following is a full, clear, concise, and exact description, reference being had to the accompanying drawing, forming a part of this specification.

My invention relates to pulping machines and it has particular relation to the provision of simple and efficient preliminary cutting or slicing means in a machine of the character described whereby the capacity of the machine is markedly increased.

In pulping machines wherein a large mass of material is rapidly agitated and beaten by a series of paddles, or otherwise, whereby it is crushed and the fruit pulp urged through a screen, the refuse being drawn off at the end of the pulping chamber, it is highly desirable that the material be as finely divided or cut as possible prior to being fed into the pulping chamber. This has been accomplished heretofore by feeding the material against cutter blades whereby it is divided.

In practicing such a method, it is essential that the material be fed at a rapid rate against the cutter blades. Heretofore, the feeding means usually comprises a screw conveyer and the cutter knives were stationary. I find, however, that the capacity of such pulping machines may be somewhat increased by rotating the feeding conveyer and the cutter in opposite directions. The joint action of the feeding means and the cutter is such that the machine capacity may, at times, be doubled.

One object of my invention, therefore, is to provide a cutter and a means for supplying material thereto, comprising a screw conveyer, the two rotating in opposite directions.

A further object of my invention is to provide means wholly exterior of the cutting chamber whereby the two instrumentalities above designated are rotated in opposite directions. In attaining this object I provide shafts journaled one within the other and so associate gears with these shafts that they

are rotated in opposite directions. A cutter-head is mounted upon one of the shafts and a screw container extends the length of the other shaft.

For a better understanding of my invention reference may be had to the accompanying drawings, in which:

Fig. 1 is an elevational sectional view of a machine embodying my invention;

Fig. 2 is an end elevational sectional view taken on the line 2—2 of Fig. 1;

Fig. 3 is a plan view of the cutter-head used in my machine, and

Fig. 4 is a sectional view taken on the line 4—4 of Fig. 3.

Standards 10 and 11 support a frame 12 of my machine. A pulping chamber 13 is provided at the bottom thereof with a screen 14, and has mounted therein rotatable beating paddles 15. A receiving chamber 16 extends beneath the screens 14 and serve to gather and to deliver, through a spout 17, the pulp material. The refuse is gradually urged to the end of the member 13, and may be drawn off through a spout 18.

The paddles 15 are mounted upon a shaft 19 which extends entirely through the machine and is journaled in the upper portions 80 of the standards 10 and 11. The preliminary receiving chamber 20 is supplied with material through a hopper 21. The material supplied to the chamber 20 is received by a screw container 22 mounted upon a shaft 23 85 which revolves around the shaft 19. The end frame 24 of the chamber 20 provides a bearing for the shaft 23. Keyed to the shaft 19, is a cutter head 25 which closes the opening between the chambers 20 and 13. The cutter-head is provided with a plurality of knives 26 and co-operating openings 27. The material after being sliced passes through the latter openings and into the main pulping chamber 13.

Exterior to either of the food receiving chambers an internal tooth-gear 28 is keyed to the shaft 19 and therefore is rotated in the same direction as the cutter-head 25. It will be noted that the cutter-head is rotated in such direction that the knife edges are urged against the material. Another gear-wheel 29 is keyed to the shaft 23, while between the gear-wheel 28 and the gear-wheel

29 is an idler gear 30 intermeshing with said gears 28 and 29 whereby the latter gear and consequently the shaft 23 is rotated in an opposite direction to the shaft 19 and the gear 28.

5 It will be observed therefore, that in my machine all of the means, whereby the feed container and the cutter-head are rotated in opposite directions, are positioned exteriorly 10 of the food chambers and therefore no tendency for the material to be tainted by coming in contact with grease or other gear lubricant is present.

15 I find that the capacity of the pulping machine is greatly increased by arranging for this opposite rotation between the cutter-head and the screw container inasmuch as the material is forced very rapidly against the knives 26 and thereafter through the 20 openings 27 into the main pulping chamber.

25 While I have described but one embodiment of my invention it is apparent that many modifications may occur to those skilled in the art and I desire, therefore, that it be limited only by the showing of the prior art and by the scope of the appended claims.

Having thus described my invention, what I claim as new and desire to secure by Letters Patent is:

30 1. In a pulping machine, a main pulping chamber, a material receiving chamber, cutter means positioned between said chambers, conveyor means in said receiving chamber to feed material to said cutter means, and means for rotating said conveyor and said cutter means in opposite directions.

35 2. In a pulping machine, a plurality of chambers, cutter means positioned therebetween, rotatable means to operate on material in each of said chambers, and means for rotating one of said rotatable means and said cutter means in opposite directions.

40 3. In a pulping machine, a main pulping chamber, a receiving chamber, cutter means positioned between said chambers, a shaft extending through both of said chambers, a beating device mounted on said shaft in said main chamber, a conveyer mounted on said shaft in said receiving chamber, and means 45 for rotating said cutter oppositely to said conveyer.

45 4. In a pulping machine, a main pulping chamber provided with a reticulated portion, a receiving chamber aligned therewith, a rotatable cutter head between said chambers, said pulping chamber being provided with a spout at its outer end, sweeps rotatable in said pulping chamber to force the fruit through said reticulated portion and to urge the refuse through said spout, feed means in 55 said receiving chamber, and means to rotate said cutter oppositely to said feed means.

50 5. A pulping machine comprising a horizontal pulping chamber having a discharge

outlet, and provided with a screen, a sweep rotatable about a horizontal axis in said pulping chamber for forcing the pulp through said screen and for advancing the refuse along said screen to said discharge 70 opening, means for feeding the material to said chamber and a rotatable cutter between said feeding means and said chamber for cutting up the material before it is fed to the pulping chamber.

75 6. A pulping machine comprising a horizontal pulping chamber having a discharge outlet, and provided with a screen, a sweep rotatable about a horizontal axis in said chamber for forcing the pulp through said screen and for advancing the refuse toward 80 said discharge opening, means for feeding material to said pulping chamber, a cutter head located between said feeding means and said chamber, for cutting up the material 85 before it enters the chamber, said cutter head being rotatable about the same axis as said sweep.

90 7. A pulping machine comprising a horizontal pulping chamber having a discharge outlet, and provided with a screen, a sweep rotatable about a horizontal axis in said chamber for forcing the pulp through said screen and for advancing the refuse toward 95 said discharge opening, means for feeding material to said pulping chamber, a cutter head located between said feeding means and said chamber, for cutting up the material 100 before it enters the chamber, said cutter head being rotatable about the said axis as said sweep, said cutter head comprising a plate having an opening therein and a knife located adjacent the rear edge of said opening.

105 8. A pulping machine comprising a pulping chamber, having a discharge opening and a screen, a sweep rotatable in said chamber for forcing the pulp through said screen, and advancing the refuse toward said discharge opening, and means for feeding material to said pulping chamber comprising a feed screw and means for rotating said feed screw in a direction opposite to the direction of rotation of the sweep.

110 9. A pulping machine comprising a pulping chamber having a discharge opening, and a screen, a sweep operating in said pulping chamber for forcing the pulp through said screen and advancing the refuse toward said discharge opening, means for feeding material to said pulping chamber comprising a rotatable feed screw coaxial with said sweep, and a rotatable cutter located intermediate said feed screw and pulping chamber for cutting up the material 115 120 before it enters the pulping chamber.

125 10. A pulping machine comprising a pulping chamber having a discharge opening, and a screen, a sweep operating in said pulping chamber for forcing the pulp through 130

said screen and advancing the refuse toward said discharge opening, means for feeding material to said pulping chamber, comprising a rotatable feed screw coaxial with said sweep, and a rotatable cutter located intermediate said feed screw and pulping chamber for cutting up the material before it enters the pulping chamber, and means for rotating the cutter in a direction opposite the rotation of the feed screw. 10

In witness whereof, I have hereunto subscribed my name.
